UNITED STATES PATENT OFFICE.

FRANCIS M. RITES, OF PITTSBURG, PENNSYLVANIA.

VALVE MECHANISM FOR COMPOUND ENGINES.

SPECIFICATION forming part of Letters Patent No. 356,376, dated January 18, 1887.

Application filed September 27, 1886. Serial No. 214,592. (No model.)

To all whom it may concern:

Be it known that I, FRANCIS M. RITES, residing at Pittsburg, in the county of Allegheny and State of Pennsylvania, a citizen of the United States, have invented or discovered a certain new and useful Improvement in Valve Mechanism for Compound Engines, of which improvement the following is a specification.

- 10 The object of my invention is to enable the admission of steam from the high-pressure to the low-pressure cylinder of a compound engine to be effected by a single eccentric at the proper period of the piston-stroke to attain a high degree of expansion in the low-pressure cylinder without the corresponding undue compression in the high-pressure cylinder incident to the operation of valve-gears as ordinarily heretofore constructed.
- 15 To this end my invention, generally stated, consists in the combination, with a steam-engine, of a sectional distribution-valve, the sections of which govern the passage of steam through different ports, respectively, and which are independently coupled to the strap of a valve-operating eccentric at different distances from the center thereof.
- 20 To this end my invention, generally stated, consists in the combination, with a steam-engine, of a sectional distribution-valve, the sections of which govern the passage of steam through different ports, respectively, and which are independently coupled to the strap of a valve-operating eccentric at different distances from the center thereof.
- 25 The improvement claimed is hereinafter fully set forth.

- 30 In the accompanying drawings, Figure 1 is a vertical transverse section through a compound engine embodying my invention, taken at the center of the valve-chest; Fig. 2, a vertical longitudinal central section through the valve-chest, and Fig. 3 a horizontal section through the same at the line $x x$ of Fig. 2.

The engine to which my improvement is herein shown as applied is of the vertical single-acting type, having a high-pressure cylinder, 1, and a low-pressure cylinder, 2, of larger diameter, fixed side and side upon the top of a crank case or box, 3, and fitted with pistons coupled by connecting-rods in the ordinary manner to the pins of cranks set oppositely or one hundred and twenty degrees apart on a crank-shaft, 5, rotating in end bearings in the crank-case 3. Steam is admitted to and exhausted from the high and low pressure cylinders by a distribution-valve reciprocated by an eccentric, 13, in a sleeve or bushing, 11, fixed in a valve-chest, 12, located be-

tween the cylinders and provided with a series of steam-supply ports, 17, communicating with a steam-supply passage, 16, to which the main steam-pipe from the boiler is connected, 5; a series of high-pressure ports, 18, above the supply-ports 17, said high-pressure ports communicating with the piston-space of the high-pressure cylinder, a series of low-pressure ports, 24, above the high-pressure ports communicating with the piston-space of the low-pressure cylinder, and a series of exhaust-ports, 25, above the low-pressure ports, communicating with an exhaust-passage, 26, to which an exhaust-pipe, leading into the atmosphere or to a condenser, is connected.

The eccentric 13, which actuates the distribution-valve, is preferably, as in the instance shown, mounted adjustably upon the crank-shaft, so as to be varied and controlled in position by a centrifugal governor of any suitable construction, the governor illustrated being similar to that which is set forth in an application for Letters Patent filed by me September 1, 1886, Serial No. 212,351, and not constituting part of my present invention.

The distribution-valve by which admission and exhaust are effected is composed of two separate and independent sections, 3 4, each having an upper and a lower piston connected 8, by a body of smaller diameter, so as to provide an annular space between them for the passage of steam from one to another series of ports of the valve-bushing 11, and both being coupled to the strap 19 of the eccentric 13, so as to be reciprocated therewith and thereby, but in such manner, as presently to be described, that the valve-sections, while moving coincidently in the same direction, shall likewise have independent relative movements and different degrees of traverse, and are alternately caused to approach and recede from each other through a limited degree of traverse in their upward and their downward movements respectively.

The admission of steam to the high-pressure cylinder is effected by the upper piston of the lower valve-section, 3, the exhaust of steam from the high-pressure cylinder to the low-pressure cylinder by the lower piston of the upper valve-section, 4, and the exhaust of steam from the low-pressure cylinder to the exhaust-

passage 26, between the lower and the upper pistons of the upper valve-section, 4. It results from such construction and function of the valve-sections that if they be drawn more closely together on their upward traverse and moved farther apart on their downward traverse, and the upper section be given a greater traverse than the lower section, a better port-opening on both admission and exhaust and a later exhaust will be attained for the low-pressure cylinder, thus affording a higher degree of expansion, and compression will be made later in both cylinders, all of which tend to a more economical utilization of steam.

15 To impart the movements above referred to to the two valve-sections from the eccentric 13, I provide the following mechanism: The upper end of the eccentric-strap 19 is caused to move in a substantially vertical line by being coupled to a fixed bearing, 29, on the crank-case 3 by means of a pair of links, 27, journaled at one end on a pin, 28, in the bearing 29, and at the other on a pin, 23, in the upper end of the eccentric-strap. The lower valve-section, 3, is coupled by a pair of links, 22, to the pin 23, and a lateral projection, 14, formed upon the upper end of the eccentric-strap 19, substantially at right angles to a line drawn from the center of the eccentric to the center 30 of the pin 23, carries a pin, 21, which is coupled by a link, 20, to a pin on the lower end of a stem, 6, passing freely through the lower valve-section, 3, and secured to the upper valve-section, 4. The effect of such lateral connection 35 of the upper valve-section to the eccentric-strap is to impart to said section a movement corresponding to that which it would receive from an eccentric of greater throw and less angular advance than the eccentric 13, as well as to retard in both directions the movement of the upper section, 4, relatively to that of the lower section, 3, due to its connection with the strap in or substantially in line with the center thereof, thereby giving an increased traverse 40 to the section 4 relatively to the section 3, and causing its distance from the section 3 to be decreased on the upward stroke and increased on

the downward stroke of the valve, the advantageous results of which difference of traverse and variation of relative position have been hereinbefore stated.

I claim as my invention and desire to secure by Letters Patent—

1. The combination, in a steam-engine, of a distribution-valve composed of two separate and independent sections which govern, respectively, the passage of steam through different ports, and are independently coupled at different points to the strap of a single operating-eccentric, substantially as set forth. 60

2. The combination, in a steam-engine, of a distribution-valve composed of two separate and independent sections which govern, respectively, the passage of steam through different ports, a single operating eccentric and strap, and link-connections in and out of line, respectively, with the center of the eccentric-strap, and coupling the valve-sections independently thereto, substantially as set forth. 65

3. The combination, with a compound engine 70 having a high-pressure and a low-pressure cylinder, of a valve-chest having a port or ports leading to the high-pressure cylinder, a port or ports leading to the low-pressure cylinder, and a port or ports leading to the exhaust, a distribution-valve composed of two separate and independent sections, the high-pressure section of which governs admission and exhaust of steam to and from the high-pressure ports, and the low-pressure section admission of steam from the 75 high-pressure to the low-pressure ports and exhaust from the low-pressure to the exhaust-ports, an operating eccentric and eccentric-strap, and links coupling the high-pressure section to the eccentric-strap in or about in line 80 with its center and coupling the low-pressure section to a lateral arm or projection on the eccentric-strap, substantially as set forth. 85

In testimony whereof I have hereunto set my hand.

FRANCIS M. RITES.
